F. W. BROCKSIEPER, OF NEW HAVEN, CONNECTICUT, ASSIGNOR TO
SARGENT & CO., OF SAME PLACE.

Design No. 3,691, dated October 5, 1869.

DESIGN FOR A LATCH-HANDLE.

The Schedule referred to in these Letters Patent and making part of the same.

To all whom it may concern:

Be it known that I, F. W. BROCKSIEPER, of New Haven, in the county of New Haven, and State of Connecticut, have invented a new Design for Latch-Handle; and I do hereby declare the following, when taken in connection with the accompanying drawing, to be a full, clear, and exact description of the same, and which said drawing constitutes part of this specification, and represents a front view.

This invention relates to a design for the handles of doors for thumb-latches, in which the handle ter-

minates, at each end, in a plate, by means of which the handle is secured to the door; and

The invention consists in the ornamentation of the said handle, as fully shown in the accompanying illustration.

I claim, as my invention—

The design for door-latch handles herein described and shown.
